(57) **CLAIM**

The ornamental design for a line lamp, as shown and described.

DESCRIPTION

FIG. 1 is a perspective view of a line lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the line lamp shown in an environment of use;

FIG. 10 is an enlarged view of portion 10 shown in FIG. 1;

FIG. 11 is an enlarged view of portion 11 shown in FIG. 9;

FIG. 12 is an enlarged left side view of FIG. 5; and,

FIG. 13 is an enlarged right side view of FIG. 6.

The dash-dash broken lines in the drawings depict environmental subject matter only and form no part of the claimed design.

The dot-dash lines in FIGS. 1, 5, 6, 9, 10, 11, 12 and 13 are for the purpose of annotating the enlarged views and form no part thereof.

1 Claim, 13 Drawing Sheets
